UNITED STATES PATENT OFFICE.

SEWARD HOMER CALKINS, OF NEW YORK, N. Y., ASSIGNOR TO TRAITLE MARBLE COMPANY, OF LONG ISLAND CITY, NEW YORK, A CORPORATION OF NEW YORK.

SETTING TOOL FOR PATTERN AND GUIDE STRIPS.

Application filed January 30, 1922. Serial No. 532,749.

To all whom it may concern:

Be it known that I, SEWARD HOMER CALKINS, a citizen of the United States, and a resident of the city of New York, Long Island City, borough of Queens, in the county of Queens and State of New York, have invented a certain new and useful Improvement in Setting Tools for Pattern and Guide Strips, of which the following is a specification.

This invention relates to an improved setting tool for pattern and guide strips of the character shown in Patent No. 1,371,857 granted to me March 15, 1921, and also to the method of setting the guide strip in position.

The present invention has for its primary object to provide a simply constructed tool whereby the pattern and guide strips may be accurately set in the bed of plastic material with ease and facility.

The invention further comprehends a new and improved method of setting the strips in position and preparing the surface of the screed coat or underbed for the reception of the plastic surface layer of the floor or wall. My new method results in a more effective fixation of the strip in the underbed prior to the application of the surface material and also produces a better union of the surface layer with the screed coat or underbed adjacent to the pattern and guide strips.

In carrying out my improved method I provide a pattern and guide strip having certain improved features of construction whereby greater rigidity and resistance to bending or distorting strains in the setting of the strip is secured.

With the above and other objects in view, the invention consists in the improved setting tool, and likewise in the novel features of the pattern and guide strip, together with the method of setting the strip and preparing the underbed, all as will be hereinafter more fully described, illustrated in the accompanying drawing and subsequently incorporated in the subjoined claims.

In the drawing wherein I have illustrated one practical embodiment of the invention and in which similar reference characters designate corresponding parts throughout the several views:

Figure 1 is a perspective view showing a portion of the improved setting tool with a

section of the guide strip associated therewith.

Fig. 2 is a transverse section taken on the line 2—2 of Figure 1;

Fig. 3 is a similar section taken on the line 3—3 of Figure 1;

Fig. 4 is a fragmentary perspective view illustrating the manner of setting the guide strip and preparing the underbed;

Fig. 5 is a detail transverse section through a completed section of the floor, and

Fig. 6 is a fragmentary perspective view showing two of the guide strips arranged at right angles to each other.

In the accompanying drawing I have illustrated a form of the setting tool which has given highly satisfactory results in practice. Nevertheless the drawing is to be considered as largely illustrative since the tool might be made in various forms and of many different sizes and shapes. In the present disclosure I have shown the tool as consisting of a body bar 5 of the desired length and slightly tapering in width from its central portion to its opposite ends. This body bar is preferably, though not necessarily, provided upon one side thereof with a transversely projecting flange 6, extending for substantially the entire length of the bar. In spaced relation to each end of the body bar an angular off-set 7 is formed in the flange 6, said off-set being disposed below the plane of said flange and having its lower face 8 slightly spaced above the plane of the lower edge face 9 of the body bar 5. The flange 6 at the ends of the off-set 7 is connected to the body bar 5 by webs 10.

On the opposite side of the bar 5 and in line with the off-set portions 7 of the flange 6, transversely projecting flanges 11 are formed, the lower faces 12 of said flanges being disposed in the same plane with the lower faces 8 of the off-sets 7 in the flange 6 and preferably of equal length and width. The ends of the flanges 11 are also connected to the body bar 5 by webs 13.

A vertically disposed groove or kerf 14 is formed in the lower portion of the bar 5 and opens upon the face 9 thereof, said kerf extending the entire length of said bar. It will be noted that the lower edge face 9 of the bar 5 extends in a single continuous plane for the entire length of the bar. The upper edge of the kerf 14 also extends

throughout the length of the bar in a plane parallel to the plane of the face 9 and also in parallel relation with the plane of the bottom faces 8 and 12 of the flanges 7 and 11. 5 The importance of this arrangement of the several surfaces or faces of the tool in parallelism with each other in the operation of setting the pattern and guide strips in place will more fully appear from the following 10 description.

As fully disclosed in my prior patent above identified, in the laying of floors, walls or ceilings of plastic materials and particularly where it is desirable to provide 15 what is known as the "terrazzo mosaic," I employ pattern and guide strips which are embedded and anchored in the screed coat or in the bed of concrete and which are arranged or set in position in accordance with 20 a predesigned pattern. This pattern is worked out by the laying of different colored sections of concrete or other plastic material between the pattern and guide strips, the upper edges of the anchored 25 strips constituting a height or thickness controlling guide for the surface material, while the strips prevent the commingling of the differently colored plastic areas and produce clear lines of demarkation between 30 the adjacent colored sections of the flooring. Such a pattern and guide strip I have illustrated in connection with the improved setting tool in the accompanying drawing. This strip, generally designated by the 35 numeral 15, is preferably though not necessarily, produced from thin sheet brass and at intervals in the length of the strip, pairs of anchoring wings or flanges 16 are struck from the body of the strip, the two flanges 40 in each pair projecting horizontally from the opposite sides of the strip and in planes at right angles to the body of said strip. The provision of these flanges 16 results in the formation of openings 17 in the body of 45 the strip, and preferably the flanges 16 are of such width that the body portions 18 of the metal strip remain at the outer sides of the openings 17 which constitute connecting bridges between the parts of the strip body 50 at the opposite ends of said openings. The point of juncture at the inner ends of the flanges 16 with the body of the strip is located substantially midway between the opposite longitudinal edges of the strip. By 55 the provision of the bridge portions 18 at the outer sides of the openings 17, it will be understood that each longitudinal edge of the strip is continuous and uninterrupted throughout the length of said strip.

60 In the use of my invention in laying floors, walls, ceilings or the like, a suitable foundation 19 of any kind is first provided upon which the lower bed or screed coat 20 of plastic material, such as cement, sand, and in some cases, gravel, is placed. The

materials of this screed coat or underbed are mixed in the proper relative proportions to provide a comparatively firm and compact bed. Upon the upper surface of this bed, after it has been properly leveled, the design 70 for the "terrazzo" surfacing material is laid out. This may be done either by "snapping" lines in red or black chalk, or by first preparing a stencil of the design and then transferring the design by means of lamp black or other suitable material upon the surface of the bed. One of the strips 15 is inserted at one of its edges in the kerf 14 of the setting tool 5 until the lower edge face 9 of the tool body is engaged upon the wings 80 or flanges 16. The other edge of the strip is then disposed upon the guide line marked on the surface of the bed 20 and by applying pressure upon the top edge of the tool, said strip is driven firmly down into the underbed until the surfaces 8 and 12 of the flanges 7 and 11 come into contact with the body surface of said bed. Obviously, since the lower edge of the body bar 5 extends below the faces 8 and 12 of the flanges, the wings 85 or flanges 16 of the strip will be forced down into the surface of the underbed and below the plane of said surface. At the same time the lower edge of the body bar acts as a tamper at each side of the guide strip 15 so 90 as to closely compact the material of the underbed. Preferably, provision is made for the lower edge of the body bar to sink into the surface of the underbed for a distance of approximately 1/16 of an inch. Thus there 95 is produced in the surface of said bed at each side of the strip a continuous longitudinally, extending depression or channel as shown at 21 in Figure 4 of the drawing.

After the guide strip has been properly 100 set in the underbed as just explained, the tool is removed. Owing to the tamping of the underbed at each side of the strip, the latter is securely held in a fixed position 105 during the hardening of the underbed. The portion of the guide strip 15 projecting above the surface of the underbed determines the height or thickness of the terrazzo surfacing material. Preferably, the underbed 20 is made of such thickness as 110 to allow the lower edge of the strip 15 to rest on the foundation 19, though this is not essential. The cementitious or other plastic material of the underbed is homogeneously 115 united through the openings 17 of the guide strip, such union being furthered by the tamping action of the lower edge of the setting tool upon the underbed material when the guide strip is set in place, as above explained. Accordingly, it will be appreciated 120 that by the provision of the bridges or connecting portions 18 at the lower sides of the openings 17, the guide strip is firmly anchored in the underbed so that it cannot 125 work upwardly therethrough.

Between the spaced parallel pattern and guide strips extending in one direction, other strips are set into the underbed 20 extending at an angle with respect to the first 5 strips in conformity with the pattern. In order to permit of the close arrangement of the ends of the latter strips against the sides of the first strips, the bar 5 of each setting tool on one side is provided with spaced recesses or notches 22 which are of such depth that the strip extending through the kerf 14 of the bar is exposed. Thus, as shown in Fig. 6 of the drawing, the strips 15' may be arranged at right angles to the strips 15^a 10 and with their ends in close abutting contact against one side of the latter strips without interfering with the proper use of the setting tools. It will, of course, be understood that the guide strips are of slightly 15 greater length than the tool bar so that they 20 project for a short distance beyond the ends of said bar.

After the pattern and guide strips have all been properly set in the screed coat or 25 underbed, the terrazzo surfacing material 23 is then placed upon the screed coat between the pattern strips, the differently colored materials being arranged as previously determined, in conformity with the desired 30 design. Care must be exercised by the workman in laying the terrazzo surfacing material that he does not permit such material to extend over the upper edges of the strips 15. It is preferable that he should 35 make this surface layer of slightly less thickness than the height of the upwardly projecting portion of the strip, since the edges of the strips which protrude above the level of the surfacing material will readily 40 wear down, in the finishing of the top surface in the usual manner either by a grinding machine or manually. Since all of the differently colored terrazzo sections may thus 45 be laid at the same time, the same degree of aging or seasoning of the materials is permitted, so that the wearing down of the surface in the finishing operation will be uniform over the entire area of a wall or floor 50 surface.

50 Owing to the fact that in the setting of the strips 15 by means of my improved tool, the anchoring flanges 16 are sunk into or embedded in the surface of the screed coat 20 and the longitudinal channels or gutters 55 21 are formed in said surface at each side of the guide strips, when the surfacing material is laid, such material will fill up the depressions or countersinks occupied by the flanges 16 and also the channels or gutters 60 21, and thereby result in a firmer and more secure anchorage of the guide strip in place than would be possible if the flanges 16 merely rested upon the upper surface of the underbed. Also, the interlocking effect 65 which is obtained by the provision of the

gutters or channels 21 between the underbed and the terrazzo surfacing material, produces a floor or wall structure of greater stability, reducing to a minimum the liability of fracture of the separate sections of 70 the surface layer adjacent to the metal pattern strips.

From the foregoing description considered in connection with the accompanying drawing, the construction, manner of operation and several advantages of my invention will be clearly understood. By means of the improved setting tool, the pattern and guide strips may be very easily and quickly, as well as accurately, set in position 75 in the screed coat or underbed of the wall or floor. It will be seen that by means of such a tool, a uniform pressure is exerted upon all portions of the metal guide strip throughout its length so that when the setting tool is removed, the upper edge of the guide strip will extend in a plane parallel 80 with the surface of said underbed. Thus the strip provides a very serviceable level and depth guide for the top surface or layer 85 and enables the latter to be quickly laid and properly finished with a minimum of manual labor. The strips 15 are quite flexible so that they may be readily arranged in curved form for working out different designs. Therefore, though I have illustrated in the drawing a setting tool having a straight continuous body bar, it will be understood that I also contemplate providing 90 these tools in various other forms and shapes.

Furthermore, in so far as the detail features of this tool are concerned, they are susceptible of certain modifications and I, therefore, reserve the privilege of constructing said tool in numerous alternative forms and of resorting to all such legitimate changes in the form, construction and relative arrangement of the several parts as may 100 be fairly embodied within the spirit and scope of the invention as claimed.

I claim:

1. For use in connection with a pattern and guide strip, a setting tool comprising a body bar having a flange projecting transversely from one side thereof and adjacent to one longitudinal edge of the bar, said bar being provided with a longitudinally extending kerf opening upon the said edge thereof and adapted to receive a portion of the metallic pattern and guide strip, and press it into the plastic material, said flange being adapted to engage the surface of plastic material and act as a stop, the edge of the bar at each side of said kerf providing means for tamping the plastic material on opposite sides of said strip.

2. For use in connection with a pattern and guide strip for floors of plastic material, a setting tool having a vertical and horizontal

member, comprising a body bar having a longitudinally extending kerf to receive and press against one edge portion of said strip and provided with flanges to engage the surface of a body of plastic material on opposite sides of said strip and limit the penetration of the opposite edge of said strip into the material while permitting the edge of said bar, under pressure, to sink the horizontal portion of the strip into said surface below the level of the underside of said flanges and thereby tamp the material on each side of said vertical portion of said strip.

3. For use in connection with a pattern and guide strip for floors of plastic material, a setting tool comprising a body bar having flanges projecting from opposite sides thereof, and having an edge of the bar extending below said flanges, said edge of the bar being provided with a kerf to receive one edge portion of said strip and said flanges adapted for contact with the surface of a bed of plastic material to limit the penetration of the other edge portion of the strip into the material, said edge of the body bar below said flanges constituting means for tamping the plastic material and forming a longitudinal channel in the surface of said material at each side of said strip.

4. A setting tool for use with pattern and guide strips for floors of plastic material, comprising a body bar, having a longitudinally extending kerf in one edge thereof to receive one edge portion of the strip, said bar providing means for applying a uniform pressure upon said strip throughout its length to force the other edge portion of the strip into a bed of plastic material to a desired depth, and stop flanges projecting from the opposite sides of said bar to engage the surface of the bed of plastic material and limit the penetration of the guide strip.

5. A setting tool for use with pattern and guide strips for floors of plastic material, comprising a body bar of substantially the same length as the strip, having a longitudinally extending kerf in one edge thereof to receive one edge portion of the strip, said bar providing means for applying a uniform pressure upon said strip throughout its length to force the other edge portion of the strip into a bed of plastic material to a de-

sired depth, and said body bar being provided with spaced recesses in one side thereof exposing the edge portion of the guide strip engaged in said kerf to permit of close contact of the end of a second guide strip with one side of the strip arranged in said kerf.

6. In the art of laying floors of plastic material, having pattern and guide strips set in the underbed of plastic material and projecting above the surface thereof, that step which consists in forming a compressed longitudinal channel in the surface of the underbed at each side of the pattern and guide strips to receive and interlock with the plastic material of a surface layer.

7. A floor of plastic material consisting of an underbed of plastic material, pattern and guide strips having one edge portion set into the surface of the underbed for a predetermined depth and provided with anchoring flanges projecting from opposite sides thereof and sunk into the underbed below the plane of its upper surface, and a surface layer of plastic material filling the depressions in the surface of the underbed occupied by said flanges, the other edge portion of the strip extending above the surface of the underbed, to provide means for determining the height or thickness of said surface layer.

8. A floor of plastic material, consisting of an underbed of plastic material, pattern and guide strips having one edge portion set into the surface of the underbed for a predetermined depth and provided with anchoring flanges projecting from opposite sides thereof and sunk into the underbed below the plane of its upper surface, the surface of said underbed being provided with channels extending longitudinally along each side of the strip between said flanges, and a surface layer of plastic material filling the depressions in the surface of the underbed occupied by said flanges and said channels, the other edge portion of the strip extending above the surface of the underbed providing means for determining the height or thickness of said surface layer.

In testimony that I claim the foregoing as my invention, and I have signed my name hereunder.

SEWARD HOMER CALKINS.
